[57] CLAIM

The ornamental design for a magnetic drill stand, substantially as shown and described.

DESCRIPTION

FIG. 1 is a right side elevational view of a magnetic drill stand showing my new design, the broken line outline indicating environmental supported drill structure, which is for illustrative purposes only;

FIG. 2 is a left side elevational view thereof;

FIG. 3 is a rear elevational view thereof;

FIG. 4 is a front elevational view thereof;

FIG. 5 is a top view thereof, with a part removed, and;

FIG. 6 is a perspective view.

FIG. 2FIG. 3FIG. 4FIG. 5

FIG. 6
